CLUTCH CONTROL

Filed July 22, 1927

Inventor:
Walter S. Myers,
Inkowndale
By *[Signature]* Attorney.

UNITED STATES PATENT OFFICE.

WALTER S. MYERS, OF DARBY, PENNSYLVANIA.

CLUTCH CONTROL.

Application filed July 22, 1927. Serial No. 207,640.

The invention relates to clutch control. The object is to provide a clutch control for motors especially for motor cars, which shall operate in certain relationship with the 5 operation of the accelerator.

The invention comprises means whereby, when the accelerator is operated, by depressing the accelerator pedal, the clutch is thrown into operation, and when the accelerator 10 pedal is released and becomes inactive, the clutch likewise becomes inactive.

The invention comprises a clutch operating motor and a circuit control therefor whereby the motor operates in either direction 15 depending upon the movement of the accelerator pedal.

As a result of the means herein described:

One pedal controls the fuel supply and the 20 clutch. The clutch is always out except when the foot is applied to the accelerator.

This eliminates the usual danger resulting from operating the self-starter when the car is in gear. When the operator slows down the car to a marked degree, the clutch 25 releases, thereby preventing strain on motor which might result from this speed while in high gear.

When the accelerator is released the clutch releases and the pedal brake may be operated 30 immediately without danger of damaging the gears or stalling the motor, as often occurs when the brake is applied before releasing the clutch.

Referring to the drawings which illustrate 35 merely by way of example suitable means for effecting the invention:

Fig. 1 is a view, partly in perspective and partly diagrammatic, showing the general assembly.

Fig. 2 is part section, part elevation of the 40 accelerator and controls, on an enlarged scale.

Similar numerals refer to similar parts throughout the several views.

In Fig. 1, the clutch 7, of usual form, is 45 provided with clutch collar 8, clutch saddle 9, clutch lever 10 and clutch rod 11. This rod 11 is connected to one end of lever 12 pivotally mounted at 13. The other end of the lever, which may be bifurcated, is connected 50 to the trunnions 14 on the block 15, threaded on the threaded shaft 16 of electric motor 17. This shaft 16 is suitably journaled at its outer end as at 18 in a part of the frame 19 supporting motor 17. The circuit of the motor 55 is provided with certain fixed and movable contacts for making and breaking the

circuit and for reversing the circuit to cause the reverse movement of the motor.

Referring to Fig. 2, the accelerator pedal 20 and pedal rod 23 are connected through the 60 bell lever 21 to the carburetor link 22 in the usual way. The rod 23 is mounted in the housing 24 and is associated with the contact elements 25, 26 and 27. A spring 28 is interposed between elements 26 and 27 and a 65 spring 29 is also interposed between the contact elements and the bottom of the housing 24. A collar 23' is provided on the rod 23 seated in a recess in contact 26.

As shown by the scheme of wiring in Fig. 70 1, when elements 25 and 26 are in contact, the motor is in the generator circuit in one direction and when elements 26 and 27 are in contact the motor is in the generator circuit in the opposite direction. 75

In the position shown in Fig. 2, the accelerator and clutch are both released. Upon depressing the accelerator pedal 20, the element 26 is separated from element 25 and carried, against the tension of spring 28, into 80 contact with element 27. This brings the motor 17 into the generator circuit and causes it to rotate the shaft 16 in direction to cause the movement of block 15 towards the motor. This brings the clutch 7 into action. When 85 the pedal 20 is released the element 26 separates from 27 and contacts with 25 due to the action of spring 28. Whereupon the movement of the motor is reversed and the block 15 carried back to initial position, in which 90 the clutch is released. The pivoted contact members 30 and 31, operated by arm 32 on block 15, serve to break the circuit of the motor at the end of the required movement of block 15 in each direction. 95

The spring 29 in housing 24 permits the further movement of the accelerator after contact is made between elements 26 and 27.

Suitable electric insulation 33 is provided between the actuating parts and the elements 100 25, 26 and 27.

In operation.

The engine is started in the usual way and the accelerator can be used to prime the engine while the gear shift lever is in neutral position. At all times the clutch is released until pressure is applied to the accelerator. 105

After the engine is started and the gear shift lever moved to proper position, foot 110 pressure is applied to the accelerator pedal 20, whereupon contact is made between 26 and

27 and the motor operated to move block 15 to the right to throw in the clutch.

When the foot pressure is withdrawn from pedal 20, contact is made between 26 and 25 5 and the motor moves block 15 in opposite direction to release the clutch.

The process of building the car into high gear is merely one of applying and removing the foot from the accelerator while shifting 10 the gear lever. The foot clutch pedal is entirely eliminated.

What I claim is:—

1. In a clutch control, the combination of an accelerator and a clutch and means includ- 15 ing an electric motor and controls therefor for causing synchronous movement of the accelerator and clutch.

2. In a clutch control, the combination of an accelerator having a spring controlled foot 20 pedal, and means whereby the depression of the said foot pedal causes the operative engagement of the clutch.

3. In a clutch control, the combination of an accelerator having a spring controlled foot 25 pedal, and means whereby the depression of the said foot pedal causes the operative engagement of the clutch and the release of the foot pedal causes the release of the clutch.

4. In a clutch control, the combination of an accelerator and a clutch, an electric motor 30 for the actuation of the clutch into and out of clutch engagement, contacts in the motor circuit controlled by the accelerator-actuating means.

5. In a clutch control, the combination of 35 an accelerator and a clutch, an electric motor for the actuation of the clutch into and out of clutch engagement, contacts in the motor circuit controlled by the accelerator-actuating means, and motor controlled cut-outs 40 for limiting the movement of the motor in opposite directions.

WALTER S. MYERS.
